UNITED STATES PATENT OFFICE

114,562

DESIGN FOR A CONDIMENTS SHAKER

Frank J. Rusting, Oakland, Calif.

Application July 30, 1938, Serial No. 78,971

Term of patent 14 years

To all whom it may concern:

Be it known that I, Frank J. Rusting, a citizen of the United States and a resident of Oakland, in the county of Alameda and State of California, have invented a new, original, and ornamental Design for a Condiment Shaker, of which the following is a specification, reference being made to the accompanying drawing, forming part thereof, wherein

Figures 1 and 2 are perspective side views of a condiment shaker embodying the design of my invention.

I claim:

The ornamental design for a condiment shaker, substantially as shown.

FRANK J. RUSTING.
